Attorney

UNITED STATES PATENT OFFICE

THOMAS CARR POWELL, OF CHICAGO, ILLINOIS

ELECTRIC-CURRENT-OUTLET MEMBER

Application filed November 15, 1928. Serial No. 319,594.

The object of my said invention is the provision of an outlet member so characterized that its prong sockets can be readily found for the proper insertion therein of the prongs of a complementary member.

To the attainment of the foregoing the invention consists in the improvement as hereinafter described and definitely claimed.

In the accompanying drawings, forming part of this specification:

Figure 1 is a perspective showing one embodiment of my invention.

Figure 2 is an enlarged perspective of the outlet screw plug comprised in said embodiment.

Figures 3 and 4 are perspectives of modified outlet screw plugs, Figure 3 being partly in section.

Similar numerals designate corresponding parts in Figures 1 and 2 to which reference will first be made.

I show in Figure 1 a mop board 1 with an escutcheon 2 affixed thereto and apertured to receive in flush relation the outer end of an electric-current outlet plug 3.

The plug 3 is provided with conventional prong sockets 4, but is peculiar in that it has a depression in the form of a groove 5 across its exposed end and in communication with the outer ends of said sockets. Thus the plug can be detected and located with the finger even when the plug is not seen by an operator, and this will be appreciated as a material advantage by those who have experienced exact operation in endeavoring to connect a two prong plug or member to an outlet plug or member when the latter is overhead or is in a dark place near the floor.

My invention also contemplates making the depression 5 in marked contrast to the remainder of the exposed end of plug 3. For instance when said end is dark the depression 5 is made light by the application of light-colored paint or other material thereto, and when deemed expedient for some uses or locations

the material alluded to is luminous. Irrespective of whether it is luminous or not the depression 5 in contrast to the end of the plug or member is readily discernible, so that the plug or member may be readily located by both feel and sight when it is located in a dark or obscure portion of a room.

Within the purview of my invention the depression 5 may be in the form of a groove or any other shape.

In the modified plug or member 3^a, Figure 3, the plug or member 3^a has inserts 6 of a contrasting color to the end of the plug and arranged in line with the sockets 4, so that the said sockets may be readily discerned in a poorly lighted room and the placing of the prong-bearing member (not shown) may be facilitated without the making of an improper connection and a resulting short circuit.

The modification shown in Figure 4 is similar to that of Figure 3 except that portions 6^a of applied paint are employed in lieu of the inserts.

Manifestly when desired the inserts 6 and the painted portions 6^a may be luminous in character.

In all of the embodiments of my invention, the portions contrasting in color to the remainder of the outlet member are in a diametrical line with the prong sockets of the member and at opposite sides of said sockets; also, the exposed end of the outlet member is free from projections, the said portions contrasting in color to the remainder of the member being within the plane of the exposed end of the member. In this way the end desired is attained without appreciably increasing the cost of production of the outlet member.

As will be readily appreciated from the foregoing my improvement confers on the outlet member or plug the advantage indicated without materially increasing the cost of production of said outlet member or plug.

Having described my invention, what I

claim and desire to secure by Letters Patent is:

An electric-current outlet member having a pair of prong sockets in its exposed end and also having adjacent to and at opposite sides of said pair of sockets portions contrasting in color to the remainder of the member; said portions being in a diametrical line with the sockets and within the plane of the exposed end of the member.

10 In testimony whereof I affix my signature.
THOMAS CARR POWELL.
